United States Patent Office

Des. 180,853
Patented Aug. 20, 1957

180,853

PROJECTOR

Kenneth A. Van Dyck, South Norwalk, Conn., and John F. Herrmann, Pittsford, N. Y., assignors to American Optical Company, Southbridge, Mass., a voluntary association of Massachusetts

Application December 18, 1956, Serial No. 44,243

Term of patent 14 years

(Cl. D61—1)

Fig. 3

Fig. 4

Fig. 1 is a side front perspective view of a projector showing our new design;

Fig. 2 is a front perspective view of the projector;

Fig. 3 is a side perspective view of the projector; and

Fig. 4 is a top plan view of the projector.

The characteristic features of the new design reside in the portions shown in full lines in the drawings.

We claim:

The ornamental design for a projector, substantially as shown and described.
